UNITED STATES PATENT OFFICE

148,785

DESIGN FOR A FURNACE

Warren B. Green, Darien, Conn., assignor to
Sears, Roebuck and Co., Chicago, Ill., a corpora-
tion of New York

Application October 5, 1945, Serial No. 122,573

Term of patent 14 years

(Cl. D81—1)

To all whom it may concern:

Be it known that I, Warren B. Green, a citizen of the United States and a resident of Darien, in the county of Fairfield and State of Connecticut, have invented a new, original, and ornamental Design for a Furnace, of which the following is a specification, reference being had to the accompanying drawing, forming a part thereof.

Fig. 1 is a perspective view of a furnace embodying my new design; and

Fig. 2 is a side elevational view thereof on a slightly reduced scale.

The dominant features of the design reside in the portions shown in full lines.

I claim:

The ornamental design for a furnace, substantially as shown and described.

WARREN B. GREEN.
